(57) **CLAIM**

The ornamental design for a grow light, as shown and described.

DESCRIPTION

FIG. 1 is a perspective view of a grow light;

FIG. 2 is a bottom view of the grow light of FIG. 1;

FIG. 3 is a top view of the grow light of FIG. 1;

FIG. 4 is a right-side view of the grow light of FIG. 1;

FIG. 5 is a left-side view of the grow light of FIG. 1;

FIG. 6 is a front view of the grow light of FIG. 1;

FIG. 7 is a back view of the grow light of FIG. 1; and,

FIG. 8 is another perspective view of the grow light of FIG. 1.

Broken lines illustrate environmental features and form no part of the claimed design.

The illustrated grow light features a unique ornamental appearance over the prior art.

1 Claim, 6 Drawing Sheets
